(57) **CLAIM**

The ornamental design for an element of a modular battery cover, as shown and described.

DESCRIPTION

FIG. 1 is a perspective view of an element of a modular battery cover showing our new design;

FIG. 2 is a perspective view of the underside thereof;

FIG. 3 is a top plan view thereof;

FIG. 4 is a perspective view thereof shown in use; and, FIG. 5 is a perspective view of the underside thereof shown in use.

The broken lines shown represent environmental subject matter only and form no part of the claimed design.

1 Claim, 5 Drawing Sheets
